UNITED STATES PATENT OFFICE.

CHARLES W. BOWEN, OF LYNN, MASSACHUSETTS, ASSIGNOR TO UNITED SHOE MACHINERY COMPANY, OF PATERSON, NEW JERSEY, A CORPORATION OF NEW JERSEY.

HEEL-BUILDING MACHINE.

1,146,996.

Specification of Letters Patent. Patented July 20, 1915.

Application filed August 16, 1907. Serial No. 388,827.

To all whom it may concern:

Be it known that I, CHARLES W. BOWEN, of Lynn, in the county of Essex and State of Massachusetts, have invented certain new and useful Improvements in Heel-Building Machines, of which the following is a specification.

This invention relates to heel-building machines, and consists of a machine by which a heel is built up of a series of lifts which are automatically assembled successively.

The assembling of the lifts in the illustrated embodiment of the invention is effected by arranging in a series a plurality of lift hoppers or magazines, and moving a heel carrier so as to pass the magazines successively and take from each a lift in such way that it builds up into a heel pile those taken from the previous magazines.

In addition to the mechanism for automatically assembling the lifts to form a heel, the invention also consists of means for securing together the lifts forming the heel by applying cement to the lifts individually, and, as a further refinement, means for finally securing together all the lifts of a built-up heel by driving a fastener therethrough.

Referring to the drawings illustrating the preferred embodiment of the invention, forming a part of this specification, Figure 1 is a side elevation of a heel-building machine embodying the invention. Fig. 2 is a partial end elevation and partial vertical section looking from front to rear. Fig. 3 is a longitudinal vertical section on a larger scale of the front portion of the building mechanism. Fig. 4 is a top plan view of the driving mechanism for reciprocating the heel carrier. Fig. 5 is a top plan view of the rack and pinion by which movement is imparted to the cement brushes. Fig. 6 is a longitudinal vertical section of a nail-driving mechanism and two of the lift magazines. Fig. 7 is a top plan and section on the line $x-x$ of Fig. 6. Fig. 8 is an elevation of a part of the nail-driving mechanism. Fig. 9 is a top plan view and section of the nail picker. Figs. 10 and 11 are detail views of tripping mechanism by which the spring driver is controlled.

Before proceeding to a description of the machine, I desire to have it understood that

the terms used herein are intended for the purpose of description and not of limitation, and that the invention is capable of a variety of other embodiments in addition to that illustrated. In this connection particular attention is called to the use, throughout the specification and claims, of the term "lift" to designate the layers or blanks of which the heel produced by the machine is composed. The term "lift" is used herein in an inclusive sense as defining any blank or layer of material capable of being used in the formation of a heel pile, from which a heel is ultimately produced, irrespective of the particular shape of the blank or the nature of the material of which it is composed.

The same reference characters indicate the same parts wherever they occur.

In the embodiment of the invention illustrated in the drawings 10 is a bed plate, above which is a series of magazines each 75 open at the bottom and adapted to contain a pile of heel lifts a . The bed plate 10 is supported on longitudinally extending frame pieces 11 and 12, which are supported in parallel relation upon upright frame pieces 80 13, 13. The frame pieces 11 and 12 are formed with guides 14, 14, on which a carriage 15 is adapted to slide back and forth under the lift magazines and below the bed plate 10. The carriage 15 is provided with 85 a movable carrier 16 having a finger 17 which extends through a longitudinal slot 18 in the bed plate, and which is actuated so as to abut against and remove the bottom lift from each pile of lifts as the carriage is 90 moved in one direction.

The series of magazines extends from front to rear of the bed plate 10 so that the carriage 15 passes under them successively, and they are arranged at successively 95 greater heights above the bed. This arrangement of the magazines is for the purpose of permitting the passage thereunder of the increasing pile of lifts of which the finger 17 removes one from each magazine. 100 Each magazine comprises a hopper 20 supported on a two-piece bottom plate 19 of which the two pieces are separated by a space sufficient for the passage therebetween of the pusher finger 17. Each hopper 20 is 105 adapted to contain a pile of lifts; and, in order to permit the removal of the lowermost lift, the rear portion of the bottom edge

of the hopper is cut away as indicated in Fig. 3, by the numeral 21. The outer edges of the bottom plate 19 are affixed to vertical adjustable blocks 22 mounted on brackets 23 affixed upon the bed 10. The blocks 22 are adjusted by means of screw-threaded studs 24 extending therethrough and bearing upon the bed. The bottom plate 19 of the first magazine preferably touches the bed as shown at the left of Fig. 3, and the successive bottom plates are at successively higher planes, each plate being as high above its predecessor as the thickness of one lift. Inasmuch as the bottom lift of each successive magazine is higher than that of the preceding magazine, it is necessary to correspondingly elevate the finger 17 step by step as it advances, so as to cause it to engage the edge of the bottom lift of each magazine. For this purpose, the carrier 16 is provided with trundle rolls 25 which run upon tracks 26. The plane of the tracks immediately below the magazines is preferably parallel with the path of movement of the carriage, but inclined between the magazines so as to cause the rolls 25 and carrier 16 to rise between each two adjacent magazines. The drawings (Figs. 1 and 3) illustrate tracks made in sections, comprising adjustable members 27 and hinged connecting members 28. The adjustable members are mounted on adjusting studs 128 with which they have screw-threaded connection, the studs being stepped in bearings on longitudinal rails 29, of which one is affixed to each of the side frames 11 12 (see Fig. 2). The carrier 16 is so mounted in the carriage that it is moved longitudinally of the machine by the carriage and relatively to the carriage by the tracks 26 which elevate it, while a spring 30, interposed in the carrier and engaging a portion of the carriage, tends to move the carrier in the opposite direction so as to hold the rolls 25 against the tracks. In the operation of building up a heel *a* contained in the several magazines, the carriage 15 starts from the position in which it appears in Figs. 1 and 3, and moves from left to right, or from front to rear of the machine. Although there are ten magazines illustrated, it is not intended that the invention should be limited to that number. Assuming that it is desired to build up a heel having ten lifts, the magazines 20 and the carrier tracks 26 are adjusted so as to cause the finger 17 to engage and remove the bottom lift from each of the piles in the magazines. Movement of the carriage causes the finger 17, which extends through the slot 18 in the bed, to pass between the two halves of the supporting plate 19 of the first magazine and to abut against the edge of the bottom lift *a* of that pile. The finger continues to move under the second lift of the pile meanwhile pushing the bottom lift

through the opening 21 at the rear of the magazine. As soon as the first lift is pushed beyond its plate 19, it lies upon the bed plate 10, bridging the slot 18 on which it is guided from one magazine to the next by guide plates 31 which prevent the lateral displacement of the lift. The latter are provided with slots 32 giving them a range of adjustment so that they may be clamped on the bed by their screws 33 so as to accommodate lifts of any desired width, see Fig. 7.

As the finger 17 passes to the second magazine, the rolls 25 of the carrier pass over the first pair of hinged members 28 of the tracks 26 to the first pair of adjustable members 27, which are at a higher plane than that portion of the track under the first magazine. The inclined portions 28 cause the rolls, together with the carrier 16 and finger 17, to rise relatively to the bed 10 and the first lift thereon. The elevation of the portions 27 is such as to cause the end of the finger 17 to rise above the top of the first lift almost if not quite as much as the thickness of another lift. Continued movement of the carriage then causes the finger 17 to push the first lift under the relatively elevated supporting plate 19 of the second magazine, whereupon the now elevated finger abuts against the edge of the bottom lift of the said hopper. The last named lift is then pushed through its outlet 21, and, when free of its plate 19, it lies upon the lift which was removed from the first magazine. The carriage advances, passing successively under the magazines, the finger 17 meanwhile rising step by step, and removing the bottom lift from each magazine as described in connection with the first and second magazines.

After having passed all of the magazines and having removed a lift from each, the finger 17 pushes the pile of ten lifts a short distance beyond the last magazine as shown at *c* Fig. 6, where it subsequently receives a nail to bind the lifts together. Thus the withdrawn lifts are transferred to a common point. As the heel *c*, shown in Fig. 6, is built up of lifts of different sizes, it will be apparent to those skilled in the art that the ten magazines hereinbefore described are constructed to hold stacks of heel lifts of different sizes respectively. In order to permit the machine to build heels having all, or a portion of its lifts, of the same size, the magazines are removable and interchangeable by simply unscrewing the studs 24, see Figs. 2 and 7, so that any desired combination of lifts may be assembled in a pile. Although the drawings illustrate somewhat conventionally a convenient form of nailing mechanism, the latter is not essential as a part of a heel-building machine, for it will be understood that, instead of that, the heel lifts might be fastened by a

nail driven manually. The last pair of guide plates 31 are provided with spring clips 34 which hold the lifts intact in the form of a heel during the operation of the 5 nailing mechanism hereinafter described. Meanwhile the carriage 15 returns to its initial position so as to repeat the building operation. During the return trip of the carriage, the finger 17 again engages the now 10 bottom lifts in the magazines, but it is ineffectual by reason of being mounted so as to be displaced by them. The finger is shown in Figs. 2 and 3 as being mounted between two ears 35 and upon a pivot 36 extending therethrough. Shoulders formed on the under side of the finger are adapted 15 to engage the supporting carriage, and, while they permit a certain amount of tilting movement of the finger, they limit the same 20 so that the finger cannot tilt forward when set at its initial position as in Figs. 1 and 3. It can, however, tilt rearwardly from this position, but, with slight friction which is afforded by the ears 35, it remains in 25 whatever position it is left. In returning to the front of the machine after leaving a heel between the clips 34, the finger 17 is caused by its engagement with the bottom lift in the rear magazine to tilt rearwardly 30 until its free end dips below the lift, and so to dip step by step as it engages each succeeding bottom lift. After passing the forward magazine, a nose 37 formed on the finger abuts against an adjustable stop 38, 35 by means of which the finger is tilted forwardly and upwardly to its original upright position. The finger is then in operative position ready for the next trip of the carriage toward the rear of the machine.

40 Any form of mechanism may be employed to reciprocate the carriage 15 in its guides 14, that here shown comprising cords 40 (or other flexible power transmitter) which pass around idle pulleys 41 41. The outer 45 ends of the cords 40 40 are attached to the carriage, and their inner ends are made fast to a driving pulley 42. The latter is affixed upon a rotatable shaft 43 which is driven alternately in opposite directions. For this 50 purpose, the shaft is provided with a pinion 44 which intermeshes with a reciprocating rack 45. The rack is pivotally connected to one end of a pitman 46 whose other end is connected to a crank 47 formed on a 55 prime power shaft 48. 49 and 50 are the driving pulley and bolt by which the shaft 48 is rotated continuously in one direction, this being transmitted to the shaft 43 by the connections described in the form of oscillatory movement.

As a detail of construction, each lift magazine 20 is provided with an adjustable gate 51 (see Figs. 3, 6 and 7) for gaging the 60 depth of the opening through which the lifts are removed. The gate is clamped

by screws 52 to the rear of the magazine and is slotted as at 53 so that it may be elevated more or less relatively to the opening 21, and its lower edge set so as to overlap the second lift from the bottom, whatever the 70 thickness of the lifts may be, and to permit the removal of only the bottom lift.

The nailing mechanism illustrated is located at the rear of the machine, and is adapted to be automatically controlled and actuated so as to drive a nail into the heel deposited between the spring clips 34. It includes a reciprocating driver 55, a nail hopper 56, a delivery nozzle 57 and a race 58 for conducting the nails 5 from the hopper to the nozzle. Although it is not shown in detail, it may be presumed that the hopper 56 is provided with a feeder for placing the nails in the race. The driver 55 is mounted on a reciprocating crosshead or 85 yoke 59, and its free end is guided toward and from the work in the throat of the delivery nozzle 57. Interposed between the throat of the nozzle and the race is an oscillatory picker 60 having a notch 61 which receives the foremost nail in the race and transfers it to an aperture 62 in the nozzle. A nail placed in this aperture gravitates into the throat of the nozzle and finally descends to a divided nail holder comprising the two 90 halves 63 63 (see Fig. 7). Each half is pivotally mounted on a fixed stud 64 and provided with a segment of teeth which intermesh, so that movement of one half communicates movement to the other half. A spring 66 holds the halves normally so 95 that the supporting ends abut against each other. Each of the latter ends has a tapered notch 67 on its co-operative face, the two notches forming a split pocket into which the point of a nail may rest until driven. The nail holder is located directly above the built-up heel, so that, when the driver 55 descends upon the nail therein, the point of 100 the latter wedges apart the halves of the holder and enters the heel. For oscillating the picker 60 so as to place the nails one at a time in the aperture 62, the crosshead is provided with an actuator in the form of a fork 68 which straddles a stud 69 extending radially from the picker. The legs of the fork are so formed that, as they descend with the crosshead, they deflect the stud 69 slightly, thereby causing the picker to place 105 a nail in the aperture 62. The driver meanwhile descends to drive the nail already placed in the holder 63 and consequently occupies the throat of the nozzle, so that the oncoming nail in the aperture 62 is prevented by the driver from entering the 110 throat until the driver again rises. When it does rise above the aperture 62, the nail contained therein gravitates to the holder 63 and is ready to be driven into the next heel.

115 The crosshead 59 is mounted upon and re-

ciprocated by a pair of parallel rods 70 70 which move in bearings 71 on the frame. The rods are provided with collars 72 and helical springs 73 which exert their tension against the collars to depress them and drive the nail. Automatic mechanism is employed to raise the rods 70 and driver against the tension of the springs 73, and to release the same when a heel is placed under the nailing mechanism. For this purpose, the rods are connected by another yoke or crosshead 74, whose ends move in guides 75, and which is connected midway between its end to one end of a pivoted link 76. The other end of the link is connected to one end of a rocking beam 77 fulcrumed at 78. The other end of the beam is pivotally connected by a link 79 to a crank 80 formed on a rotatable shaft 81. The shaft is provided with a loose sleeve 82 having a pulley 83 and a ratchet 84. The sleeve 82 is continuously rotated in one direction as indicated by arrows in Figs. 1 and 11, by reason of being connected to the prime shaft 48 by a belt 85 passing over the pulley 83 and over a pulley 86 mounted on the said shaft. The shaft 81 is also provided with a tight sleeve 87 on which is pivotally mounted a pawl 88 adapted to coöperate with the ratchet 84. A spring 89, engaging a nose of the pawl, tilts the latter so as to normally coöperate with the ratchet and transmit rotation thereof to the shaft 81. An arm 90, pivoted on a stud 91, is adapted to engage the pawl and disengage it from the ratchet. The free end of the said arm is adapted to rest upon the periphery of the sleeve 87 and to move it into the path of the pawl when the sleeve revolves. The pawl abuts against the end of the arm and is tilted thereby against the tension of the spring 89 so that it becomes disengaged from the ratchet. A shoulder 92 on the sleeve then abuts against the pawl opposite the arm 90, and rotation of the sleeve 87 and shaft 81 is arrested. The pawl is preferably located with relation to the crank 80 so that it engages the arm 90 immediately after the crank has passed the dead point at the completion of the up stroke of the rods 70. The springs 73 are then exerting their tension to force the rods 70 downwardly and to rotate the shaft 81 in the same direction in which the ratchet 84 rotates. The pawl 88 is hereby held in engagement with the stop arm 90 and out of engagement with the ratchet until otherwise released.

For releasing the pawl, the stop arm is provided with a boss 93 which coacts with the hooked end of a bell crank 94 pivotally mounted on the free end of an arm 95. The arm 95 is affixed to one end of a rock shaft 96 on the other end of which is an arm 97 by which the shaft is rocked. The free end of the arm 97 lies in the path of movement of a

nose 99 formed on a reciprocating rod or actuator 100 extending longitudinally of the machine and mounted in brackets 101 on the frame. See Fig. 2. The ends 102, 103 of the actuator are turned at right angles to the main body thereof and extend through slots 104 in the frame member 12 (see Fig. 3), so that they lie in the path of the carriage 15 which is between them. The carriage, as it moves back and forth on its guides 14 engages first one and then the other of the ends 102 and 103 and thereby moves the actuator first in one direction and then in the opposite direction. When it moves to the rear of the machine and deposits a built-up heel *c* under the nailing mechanism, it engages the end 102, moving the actuator a short distance with it. This causes the nose 99 on the actuator to engage and move the free end of the arm 97, thereby rocking the shaft 96 so as to elevate the arm with the bell crank 94. The hooked end of the latter, which underlies the boss 93, raises the free end of the stop arm out of engagement with the pawl 88. The nailing mechanism is thereby released and the springs 73 then depress the rods 70 together with the driving head 59 and effect the driving of a nail into the heel just placed under the nailing mechanism. The bell crank 94 in its upward movement engages a fixed stop 105 by which it is tilted so as to release the boss on the stop arm 90. The stop arm then drops back until its free end strikes the sleeve 87 upon which it rests once more. The ratchet 84 meanwhile continues to revolve and picks up the pawl 88 by which it is again engaged. It turns the pawl together with the sleeve 87 until the former once again strikes the stop arm by which it is arrested as hereinbefore described. The nailing mechanism has then completed its cycle of movements and is returned to its normally operative position. The carriage 15, when it approaches its initial position, engages the end 103 of the actuator 100 and moves the latter so that its nose 99 leaves the rock arm 97. The weight of the arm 95 then causes it, together with the rock shaft and the arm 97, to assume their initial positions as illustrated by Fig. 1. In so doing, the bell crank 94 assumes its tripping position relatively to the boss 93, and all is ready to be again released when the heel carrier shall have deposited another heel under the nailing mechanism.

The invention involves, as hereinbefore stated, means for applying cement to the lifts, and this is done, excepting in the case of the last magazine, as each lift is removed from its hopper. The reason for omitting this feature in the case of the last magazine is because the only surfaces requiring cement are those which lie against other lifts, the

lift from the last magazine being on the top of the heel and upon the cement-coated surface of the lift below it.

Each magazine is provided with a cement brush 106 so mounted that its bristles wipe the upper face of each lift *a* as the latter is moved through the outlet 21 of its hopper. All of the brushes, during the operative trip of the heel carrier, occupy positions adjacent to the outlets of their respective hoppers, and, during the return trip of the carrier, they are moved laterally into engagement with a cement roll 107 from which they receive cement. Figs. 2 and 7. The roll 107 and the cement trough 108, in which it is journaled, are supported at one side of the machine and extend longitudinally thereof. A belt 109 passes over one end of the roll and over a pulley 110 on the prime shaft 48 and imparts rotation to the roll whose under side is kept immersed in cement.

Inasmuch as the cement-applying devices of each magazine are identical, a description of one will be sufficient. The stem of the brush is rigidly mounted in a laterally-extending reciprocatory rack 111 mounted in bearings in the brackets 23. The teeth of the rack intermesh with a pinion 112 mounted on the upper end of a perpendicular shaft 113 which is journaled in the brackets 23 and 101, the latter, as hereinbefore stated, supporting the actuator 100. The lower end of the shaft has a pinion 114 which intermeshes with rack teeth 115 formed on the actuator 100 by which it is rotated alternately in opposite directions. All of the shafts 113, being arranged and actuated by the actuator 100 as shown by Fig. 5, cause the cement brushes 106 to move simultaneously to a position above and in engagement with the cement roll when the heel carrier deposits a heel under the nailing mechanism. In this position the brushes remain while the heel carrier is returning to initial position. The cement roll meanwhile revolves thereby filling the brushes with cement until the carriage 15, at the end of its return trip, moves the actuator in the opposite direction. The brushes 106 are then moved to their operative positions adjacent the openings 21 of the hoppers.

While this specification and the appended claims refer to removing the lifts from the magazine "singly" or "one at a time", I do not mean thereby to limit the invention to removing only one lift from each magazine, as two or more might be removed from each magazine for a "dry" or unpasted heel without materially changing the construction of the machine, and hence I desire to have those terms construed in the light of this explanation.

Having thus explained the nature of my said invention and described a way of constructing and using the same, although

without attempting to set forth all of the forms in which it may be made, or all of the modes of its use, I declare that what I claim is:—

1. A heel-building machine comprising a series of magazines for lifts of such shape and form as to support a column of superposed lifts, mechanism for removing a lift from each magazine, and assembling it with lifts removed from other magazines, to form a heel pile, said mechanism having a part arranged to enter and pass across the bottom of each magazine to engage the lowermost lift therein, and means for engaging the lateral surface of said heel pile at separated points to exert opposing pressures on the lift edges and aline the lifts in proper register to each other. 70

2. A heel-building machine comprising a series of magazines for lifts of substantially the shape and dimensions in cross section to confine a series of superposed lifts in a column, automatic traveling assembling mechanism having a part adapted to enter the bottom portion of each magazine and pass through the same for removing lifts from said magazines successively and gathering them in a pile, and means for engaging the lateral surface of said heel pile at separated points to exert opposing pressures on the lift edges and aline the lifts in proper register to each other. 85

3. A heel-building machine comprising a series of magazines for lifts so constructed as to compel a series of superposed lifts to retain a columnar form, a guide extending beneath the magazines from each to the next in series, traveling gathering mechanism arranged to advance along said guide, and having a part arranged to displace a lift from each magazine and to carry the displaced lifts to and beneath the next magazine in such manner that each successively removed lift is superimposed upon the lift from the next preceding magazine, and means for engaging the lateral surface of said heel pile at separated points to exert opposing pressures on the lift edges and aline the lifts in proper register to each other. 100

4. A heel-building machine comprising a series of magazines, and having approximately the form and dimensions in cross section of a heel, each containing heel lifts, mechanism for taking a lift from one magazine and carrying the same past other magazines, said mechanism including a member arranged to pass across the lower part of and take a lift from each magazine and deposit it upon a lift or lifts carried from preceding magazines, and means for engaging the lateral surface of said heel pile at separate points to exert opposing pressures on the lift edges and aline the lifts in proper register to each other. 115

120

125

130

5. A heel-building machine comprising a series of magazines for lifts formed and arranged to confine a series of superposed lifts in columnar form, mechanism for building 5 a pile of lifts including a member between which and the magazines there is a relative movement, said member having a part which passes across the magazines successively in the course of such relative movement, whereby lifts are taken from each so as to place each succeeding lift upon that taken from the preceding magazine, means for producing such relative movement, and means for engaging the lateral surface of 10 said heel pile at separated points to exert opposing pressures on the lift edges and aline the lifts in proper register to each other.
6. A heel-building machine comprising a series of magazines, each having means for supporting a pile of lifts therein and confining such pile, means for taking the bottom lifts from said magazines successively, a guide extending under the magazines 15 along which the lifts are moved, by said means, whereby the subsequently removed lifts are successively piled on those taken from preceding magazines, and means for engaging the lateral surface of said heel pile at separated points to exert opposing pressures on the lift edges and aline the lifts in proper register to each other.
7. A heel-building machine comprising a bed, a series of magazines above the bed, 20 each magazine having an open bottom and means for supporting a pile of lifts therein, a carrier for taking the bottom lift from each magazine in succession and moving it along the bed under the succeeding magazines so that each succeeding bottom lift 25 may lie upon the lift taken from the preceding magazine, and cement applying means arranged between magazines to apply cement on the lift in its progress from one magazine to the next.
8. A heel-building machine comprising a bed, a series of magazines above the bed, each magazine having an outlet and means for supporting a pile of lifts therein, cement applying means beside the outlet of each, a carrier and means for moving said carrier whereby said carrier takes the bottom lift from the first magazine and moves it along the bed under the other magazines 30 in succession, and for taking the bottom lift from each succeeding magazine when the preceding lift is beneath it, so that each succeeding lift lies upon that of the preceding magazine, and the several lifts are cemented.
9. A heel-building machine comprising a plurality of heel-lift magazines arranged with their outlets in different planes, a carrier, mechanism for moving said carrier with respect to the outlets of said magazine, 35 a heel-lift-engaging member on said carrier, means for automatically positioning said member to engage and remove heel lifts from the said magazines in succession, and means for applying cement to the face of each lift after its removal from its respective magazine.
10. A heel-building machine comprising a carrier, mechanism for moving said carrier, a plurality of heel-lift magazines arranged above the path of the carrier with their outlets in successive parallel planes, cement applying means beside and above the outlet of each magazine, a lift-engaging member on said carrier, and means for moving said member to cut said planes successively and thereby engage the lifts successively and place each lift under the lift of the next succeeding magazine, after passing the adjacent cement applying means and receiving deposits of cement therefrom.
11. A heel-building machine comprising a nail supplying and driving mechanism, a series of stationary magazines for containing lifts, and traveling means arranged to pass the magazines in succession and take a lift from each of the magazines and arrange the lifts in the form of a heel and deliver the same to the nailing mechanism.
12. A heel-building machine comprising a nailing mechanism, tripping mechanism for rendering the nailing mechanism active, a series of magazines for containing lifts, and means for taking a lift from each of the magazines and arranging the lifts in the form of a heel and for delivering the same to the nailing mechanism and actuating the tripping mechanism.
13. A heel-building machine comprising a plurality of holders for containing a supply of lifts, means constructed and arranged to travel past the holders successively for removing independent lifts one by one from the several holders and arranging them one upon another in the form of a heel, and means for coating the lifts with cement as they are taken from their source of supply.
14. A heel-building machine comprising a nailing mechanism, a plurality of holders for containing a supply of independent lifts, means for removing a sufficient number of lifts one by one from the several holders to construct a heel and arranging them one upon another in the form of a heel and delivering the same to the nailing mechanism, mechanism for producing a relative movement between the holders and said removing means, whereby the said means is caused to remove a lift from each holder, and means for coating the lifts with cement as they are removed from their source of supply.
15. A heel-building machine comprising a series of magazines, each having a hopper

with an open bottom, means for supporting a pile of lifts therein, and a cement brush adjacent the bottom of the hopper; and a carrier for removing laterally the bottom lift of the first magazine so as to cause it to engage and wipe the adjacent cement brush and for moving the cement-coated lift under the other magazines in succession and likewise removing the bottom lift from each succeeding magazine so as to lay it upon the cement coated lift of the preceding magazine.

16. A heel-building machine comprising a series of magazines for containing lifts, means for removing lifts one at a time from the magazines and laying them one upon another in the form of a heel, a single source of supply of cement, and a series of cement brushes one for each magazine, movable from the source of supply to positions overlapping the paths of removal of the lifts of their respective magazines.

17. A heel-building machine comprising a series of magazines each having an open bottom and means for supporting a pile of lifts therein, a normally active nailing mechanism, normally operative controlling mechanism for rendering the nailing mechanism inactive, tripping mechanism for rendering the controlling mechanism inoperative, a carrier movable in a path under the series of magazines toward and from the nailing mechanism, for removing the bottom lift from the first magazine and moving it under the other magazines in succession, and for likewise removing the bottom lift from each successive magazine and laying it upon its predecessor as the latter passes thereunder and for finally delivering to the nailing mechanism the lifts so removed in the form of a heel, an actuator in the path of said carrier and adapted to be moved thereby so as to actuate the tripping mechanism as a heel is delivered to the nailing mechanism, a source of supply of cement, a series of cement brushes movable from said source of supply to positions adjacent each magazine wherein each brush is engaged by and coats with cement a lift as the latter is removed from its magazine, and means actuated by said actuator for simultaneously moving all of said brushes back and forth from the source of supply to their respective positions adjacent the magazines.

18. In a heel-building machine, a series of magazines for lifts, each containing independent lifts, and the number of said magazines being the same as the number of lifts necessary to build a complete heel, an organized nailing mechanism, means for removing the lifts one by one from the magazines and laying them one upon another in the form of a heel and delivering the same to the nailing mechanism, a mechanism for producing a relative movement between said

removing means and the magazines whereby said means is enabled to take a lift from each magazine, and means for applying cement to each lift as it is removed from its magazine.

19. A heel-building machine, comprising a series of magazines having means for supporting a pile of lifts in each, and having discharge openings in different planes, means arranged to move successively beneath all the magazines of the series for assembling lifts one upon another by removing a lift through the discharge opening of each magazine and carrying such lift or lifts beneath other magazines, and means for holding the lifts intact in the form of a heel and positioning them for a subsequent operation.

20. A heel-building machine, comprising a series of magazines having means for supporting a pile of lifts in each, and discharge openings in different planes, said planes being spaced from one another by distances approximately equal to the thickness of the lifts, means for removing a lift through the discharge opening of each magazine and assembling the removed lifts in substantially the planes of their removal, one upon another, mechanism for producing a relative movement between the magazines and removing means, whereby said means is enabled to remove a lift from each magazine, and means for holding the lifts intact in the form of a heel and positioning them for a subsequent operation.

21. A heel building machine, having, in combination, means for holding a series of stacks of heel lifts, means for withdrawing lifts successively from each stack, said means operating to move in succession the lifts so withdrawn past each succeeding stack of the series so as to produce a pile of lifts adapted to form a heel, and means for securing together the lifts forming the heel pile.

22. A heel building machine, having, in combination, means for holding a series of stacks of heel lifts, means for withdrawing lifts successively from each stack, said means operating to move in succession the lifts so withdrawn past each succeeding stack of the series so as to produce a pile of lifts adapted to form a heel, and fixed guides arranged beyond each stack to prevent lateral displacement in either direction of the withdrawn lifts, substantially as described.

23. A heel building machine, having, in combination, means for holding a series of stacks of heel lifts, means for withdrawing lifts successively from each stack, said means operating to move in succession the lifts so withdrawn past each succeeding stack of the series so as to produce a pile of lifts adapted to form a heel, and means for alining said piled lifts in proper register to each other

for a subsequent operation, substantially as described.

24. A heel building machine, having, in combination, means for holding a series of 5 stacks of heel lifts, means for withdrawing lifts successively from each stack, said means operating to move the lifts so withdrawn from each of said stacks in succession so as to produce a pile of lifts adapted to form a 10 heel, and a series of guides arranged in pairs beyond each stack to prevent lateral displacement of the lifts, the last pair of guides in the series being provided with means for 15 positioning the pile of lifts for a subsequent operation, substantially as described.

25. A heel building machine, having, in combination, means for holding a series of stacks of heel lifts of different sizes, and means for positively withdrawing lifts from 20 the several stacks in succession and assembling them in proper register to each other to form a heel of predetermined contour, substantially as described.

26. A heel building machine, having, in combination, a series of interchangeable hoppers for holding stacks of heel lifts of different sizes, and means for positively withdrawing lifts from a plurality of hoppers in succession and assembling them in proper 30 register to each other to form a heel of predetermined contour, substantially as described.

27. A heel building machine, having, in combination, a plurality of magazines in 35 series for holding heel lifts, a single pusher finger for engaging and withdrawing a lift from each magazine and for piling them face to face to form a heel pile, a heel former, and mechanism for operating said finger to 40 transfer said heel pile thereto to aline the lifts in proper register to each other.

28. A heel building machine, having, in combination, a plurality of magazines adapted to contain lifts of different sizes respectively, automatic means for positively engaging and withdrawing a lift from each magazine and superposing them on each other to produce a heel pile of predetermined contour, and means for cementing each lift 50 separately while the pile is being produced.

29. A heel building machine, having, in combination, means for holding a series of stacks of heel lifts, means for withdrawing a lift from each stack and superposing the 55 lifts so withdrawn on each other so as to produce a pile of lifts adapted to form a heel, and additional means for engaging the lateral surface of said heel pile from base to top to aline said lifts in proper register 60 to each other.

30. A heel building machine, having, in combination, means for holding a series of stacks of heel lifts, means for withdrawing

lifts from each stack and for moving in succession the lifts so withdrawn past each 65 succeeding stack in said series, and means beyond the last stack of the series for engaging said heel pile and alining the lifts in proper register to each other for a subsequent operation.

31. A heel building machine, having, in combination, a series of magazines each having means for supporting a pile of lifts therein, a guide extending parallel to said series of magazines, means for taking a lift 75 from each of said magazines, delivering them to said guide and superposing them thereon to form a heel pile, and means at the end of said guide for engaging said heel pile and alining the lifts in proper register to 80 each other.

32. A heel building machine, having, in combination, a table, a plurality of sources of lift supply adjacent said table, means for moving a lift along said table past said 85 sources of supply and for delivering successive lifts from successive sources into assembled relation thereto to produce a heel pile, and means to which said heel pile is finally delivered for alining the lifts in 90 proper register to each other.

33. A heel building machine, having, in combination, a series of magazines for heel lifts, a device for positively engaging and withdrawing independent lifts from each of 95 said magazines, means for relatively moving said magazines and device to successive positions where said device may act on each magazine successively, a support on which said lifts are deposited by said device face to 100 face to form a heel pile, and means for securing together the lifts forming the heel pile.

34. A heel building machine, having, in combination, means for holding a series of stacks of heel lifts, a building table adjacent 105 thereto, a heel forming device adjacent said table, and means for delivering a lift from each stack to said table and thereafter transferring said lifts to the forming device to 110 aline said lifts in proper register to each other.

35. A heel building machine, having, in combination, means for holding a series of stacks of heel lifts, means for withdrawing a lift from each stack and superposing the 115 lifts so withdrawn on each other so as to produce a pile of lifts adapted to form a heel, a forming device, and means for transferring said heel pile to said device to aline said lifts in proper register to each other.

In testimony whereof I have affixed my signature; in presence of two witnesses.

CHARLES W. BOWEN.
